UNITED STATES PATENT OFFICE.

ROY H. SMITH, OF KENT, OHIO.

METHOD OF MAKING TOOLS.

Application filed November 6, 1919. Serial No. 336,117.

To all whom it may concern:

Be it known that I, ROY H. SMITH, a citizen of the United States, residing at Kent, in the county of Portage and State of Ohio, have invented a certain new and useful Improvement in Methods of Making Tools, of which the following is a full, clear, and exact description.

This invention relates to a method of making tools, and has particular reference to the manufacture of socket wrenches adapted for setting and removing rim nuts of demountable rim wheels.

The principal object of the invention is to provide certain improvements by which efficient and readily manipulated tools, particularly wrenches, can be produced very inexpensively.

In accordance with my invention, a rod or bar of suitable length and cross-section is split longitudinally for a portion of its length, and one or both bifurcations, preferably both, are bent laterally with respect to the remaining portion to form handle or manipulating portions, either or both of which may be shaped to constitute a tool, and the end of the undivided part of the bar is upset and shaped into a suitable tool head such as a socket wrench.

The invention may be further briefly summarized as consisting in certain novel steps of the improved method which will be described in the specification and set forth in the appended claims.

In the accompanying sheet of drawings showing two different forms of my invention, Fig. 1 is a perspective view of a socket wrench with a screw-driver formed on one of the handles, the same having been made by my improved process; Fig. 2 is a cross-sectional view substantially along the line 2—2 of Fig. 1; Fig. 3 is a cross-sectional view substantially along the line 3—3 of Fig. 1, this view showing by dotted lines the original shape of one of the bifurcations or split portion of the rod or bar; Fig. 4 is a side view of a tool made with a slight modification in the process; and Fig. 5 is a side view of the same with the tool turned ninety degrees from the position shown in Fig. 4.

In carrying out my invention I start with a rod or bar 10, of the proper length and cross-section, the cross-section being generally round, though this is not essential.

The area of the cross-section of the piece

will be such as is desirable for forming the shank and head of the main tool to be formed, and twice the cross-section of the handle or manipulating portions.

Then with a suitable tool, the piece is split or divided longitudinally, preferably in the center plane of the piece, from one end along the piece for a distance depending upon the desired length of the handle or manipulating portions. In Fig. 1 I have shown by dotted lines at 10^a, the split portion of the piece. Then one or both of the bifurcations or split portions thus formed are bent laterally, generally at right angles to the unsplit or shank portion 10^b. If a socket wrench is being formed, for which my invention has special utility, both split or bifurcated portions are bent laterally into alignment to form the handle or manipulating portions 10^c. With the tool shown in Fig. 1, the bifurcated or handle portions are bent laterally at right angles to the plane of cleavage of the piece, though this is not essential as will subsequently appear.

The handle portions 10^c may be left in the shape in which they are formed when the piece is split, in which event, they would be half round in cross-section, assuming that the original cross-section of the piece is round, but if desired, by means of suitable dies, the sharp edges of the handle portions may be removed by somewhat reshaping these portions, as for example, by giving them a somewhat oval shape, as shown in Fig. 3.

One or both the handle portions may be shaped to constitute tools, as indicated in Fig. 1, which shows one of the handle portions provided with a screw-driver end, 95 shown at 10^d.

Either before or after the piece is split or bifurcated as above explained, the desired tool head will be formed on the shank portion 10^b or unsplit end of the piece. In this instance, this end of the piece is provided with a head 10^e in which is formed a wrench socket 10^f. The wrench head is formed by first upsetting the end of the piece with suitable upsetting tools, and then by suitable dies, forming the socket in the upset end, these operations being performed by first suitably heating the end of the piece which is thus to be treated.

In Figs. 4 and 5 there is shown a similar

tool, with a shank portion 11^b on which is formed in the same manner as before, a wrench socket head 11^c. Likewise, this tool has handle or manipulating portions 11^e, which as in the first instance are formed by first splitting the piece downward from one end, and by bending the bifurcations thus formed, laterally into alignment, or at right angles to the shank portion. In this instance 10 the handle portions 11^e are bent in the plane of cleavage. With this form of the invention the splitting and bending can be readily done in one operation by a pair of cutting and manipulating members which swing 15 scissors-like in opposite directions.

With either form of the method above described, tools such as illustrated, can be produced with great rapidity, finished tools being formed without any machine work as 20 distinguished from that produced by means of dies, but at the same time, the tools are strong, and very serviceable and satisfactory in use.

Though I now prefer that the piece 10 be 25 split longitudinally on the center plane of the same, so that the handle portions are similar, or of equal cross-section, nevertheless the splitting could be done somewhat to one side of the center plane in the event 30 it should be desired that one of the handle portions be larger than the other, as might be the case in producing certain combina-

tion tools wherein a tool head is formed on one or on each of the bifurcated portions.

Though the invention has been described 35 chiefly in connection with the production of socket wrenches, the principle of the invention may be used for producing other tools or co-called combination tools.

Having described my invention, I claim: 40

1. The method of making tools which comprises lengthwise splitting a portion of a rod or bar, bending at least one of the bifurcations thus formed laterally with respect to the unsplit portion to form a handle or manipulating part, and forming a suitable tool head on the end of the unsplit portion. 45

2. The method of forming tools which comprises longitudinally splitting a bar or rod from one end to form bifurcations, bending at least one of the bifurcations laterally, and forming tool heads on at least one of the bifurcations and on the unsplit end of the rod or bar. 50

3. The method of making tools which consists in splitting a piece longitudinally from one end for a portion of the length of the piece, bending the bifurcations laterally to form handle portions, and forming a tool head on the end of the unsplit portion of 55 the piece.

In testimony whereof, I hereunto affix my signature.

ROY H. SMITH.
